DISHWASHING MACHINE

Arthur G. Kohler, New York, N. Y.

Application May 7, 1931, Serial No. 535,677

5 Claims. (Cl. 141—9)

This invention relates to dish washing machines and in particular to one arranged to be placed within a special tank or wash tub.

A particular object of my invention is to provide a dish washing machine which is arranged to be placed in a standard wash tub which is used for the washing of clothes and which is usually placed adjacent a sink whereby the machine, as a unit when placed in the wash tub is concealed by the cover thereof but is ready for use to wash a number of dishes, cups, saucers and eating utensils.

An advantage of my invention is that the drain of the wash tub is used to drain out the water after the dishes have been cleansed, means being provided for covering the drain opening in the tube with a suitable automatic water levelling device which permits filling of the tub to the required depth for efficient operation of the water impeller.

A still further object of my invention is to provide a compact machine comprising a main and auxiliary frames, the latter of which are employed for the support of dishes and the former of which is arranged to support a cover which fits into the upper end of the tub or tank and provides a watertight seal so that leakage at the upper part of the machine is prevented.

A still further object of my invention is to provide within the machine, a watertight motor compartment and within the main frame, a water impeller which effectively sprays the water to thoroughly cleanse the dishes and utensils.

Changes and variations may be made in the construction shown and described without departing from the principles of the invention or sacrificing its chief advantages; hence such invention is not to be confined to the structures shown in the accompanying drawings:

40 Figure 1 is a view in sectional elevation, the section being taken substantially on the lines 1—1 of Figure 3 and the dish holding frame being omitted at one side of the view for clearness of illustration.

45 Figure 2 is a section taken on the line 2—2 of Figure 1 illustrating the construction of the drain and overflow member.

Figure 3 is a top plan view of the machine, one-half of the cover being removed to illustrate 50 the construction of the frames.

Figure 4 is a view in sectional elevation of the water impeller employed in the machine.

Figure 5 is a top plan view of the water impeller illustrated in Figure 4, and

55 Figure 6 is a section taken on the line 6—6

of Figure 5 showing the development of one of the water passageways employed in the impeller.

Referring to the drawings in detail, 5 indicates a wash tube or tank in which is housed my improved washing machine. The machine is properly to be used in connection with the ordinary household wash tube but if desired, a suitable tank may be employed that can be supported in any suitable manner, it being understood that the wash tub is supported on suitable legs, a showing of which is not deemed necessary.

The wash tub is usually provided with the inner sloping walls 6 and bottom 7 upon the latter of which rests, the bottom portions 8 of a main frame 9. This main frame is made of stout wire stock and is bent at the corners as at 10 to fit the curvature of the tub or tank in connection with which the machine is employed. The main frame 9 is composed of individual pieces of wire stock which are bent to provide the bottom portions 8 which are soldered as at 11 or welded in suitable slots to a center plug 13, the slots being disposed radially of the plug and the frame portions also extending radially to the corners of the frame, where, as before mentioned, they are curved as at 10 and sloped upwardly as at 14 to provide the upstanding ends 15 which are welded or connected in any suitable manner to the exterior surface of the motor housing 16. A suitable reinforce ring 17 is employed to strengthen the bottom central portion of the main frame 9, while upper rings 18 and 18A are employed for the purpose of strengthening the main frame and holding the same rigid and at the same time providing a support for the lower section 19 of an auxiliary frame combination 20.

The main frame 9 is provided with the upstanding corner pieces or extensions 21 which are welded to or otherwise suitably secured to the cover 22 at the corners thereof. The lower section of the auxiliary frame or plate holding frame is provided with a series of convolutions constituting rests for the edges of the plates or dishes. The inner end of the lower section 19 may be welded or otherwise secured to the motor housing 16 and its convolutions 24 are longer and are disposed at an angle relatively different from the angle of the convolutions 23 in the outer extension of the lower section 19. This lower section 19 rests on the ring 18 as heretofore noted and the lower section 19 has welded or otherwise secured thereto, the inner and outer rings 25 and 26 respectively, which rings support the upper section 27 of the frame for holding the plates and by referring to Figure 3, it will be 110

noted that the sections 27 and 19 are alternately spaced peripherally of the rings 25 and 26 so that, as indicated in outline in Figure 1, the lower sections of the plate holding frame 19 support the lower edges of these plates while the convolutions of the upper section 27 support another portion of the plate or dish with the result that the dishes are substantially supported in their vertical position and at the proper angle so that the impelled water strikes them to remove the congealed matter on the plates quickly.

The outer ends of the sections 19 and 27 are extended upwardly as at 28 and 29 respectively and are secured by the upper ring 30, it being understood that the dish holding frame and the main frame 9, when the machine is completed, are a single unit and the entire machine is lifted out of the tub or tank in which it is disposed in a single piece.

20 The housing for the motor being supported as it is by the vertical end 15 of the main frame 9, is held in the proper position to accommodate the driving motor 31 which rests on the bottom 32 of the housing and has its shaft 33 protruding through a suitable opening 34 in the bottom of said housing. The shaft 33 has secured thereto, a sleeve 35, the upper end of which is secured to the impeller disk 36 in any suitable manner, the disk itself being shaped at its outer end to provide the counterweight 37 at one side and the impeller nozzle 38 at the opposite side. Both the counterweight 37 and the impeller nozzle 38 are segmental in shape and extend through an arc of any number of degrees.

35 Referring to Figures 4, 5 and 6, it will be noted that the impeller disk 36 is provided with an apron 39 to which is properly secured in any manner the counterweight 37, while the disk 36 is provided with an integral extension 40 providing a spiral flange 41 to which is secured as by welding or in any other suitable manner, the passage defining member 42, the intake end 43 of which is provided with a horizontal vein 44 to provide additional projection of the water in its passage through the water or liquid 45 of the tank. The passage defining member 42 is bent upon itself as at 46 at spaced points to define water passages, these spaced points being also welded to the flange 41 of the impeller disk so that a plurality of passages are provided which extend spirally of the impeller disk and have their outlet end disposed in vertical position as at 47, it being understood that the curvature of the passages depends upon the curvature of the flange 41 which is shaped as indicated, while the upstanding wall 48 of the impeller disk adjacent the outlet end of the impeller nozzle is extended as at 49 to provide a reinforce for the nozzle.

60 The cover 22 has hinged thereto as at 50, the lid 51, the cover 22 and the lid 51 forming a closure at the top of the machine when the same is placed in a tub or tank and being provided with the depending flanges 52 which are curved slightly outward at their lower edges as at 53 and have secured thereto in any suitable manner, the waterproof packing 54 for the purpose of sealing the machine in the tub or tank in which it is disposed. The hinge 50 consists of the hinge pin 55 and the tops of the cover 22 and lid 51 are curled about the hinge pin 55 to provide the usual hinge joint, the parts being movably joined and reinforced by the flexible strap members 56 which are secured in any suitable manner at their ends to the lid and cover 51

and 22 respectively. The member 56 is a continuous strip extending across the entire cover and lid, but may be made in pieces placed at spaced points, if so desired. A further function of this member is to prevent leakage of water when the same is thrown against the bottom of the cover by the impeller. The cover 22 carries the metal strip 58 which is engaged in its extended portion by the spring clip 59 carried by the lid 51 so that the lid is held forcibly closed during a dish washing operation.

80 The cover 22 is provided with a watertight gasket 60 through which passes the operating lever 61, whose upper end is turned in a horizontal direction and carries the handle 62 whose operation is limited through the medium of the stop plugs 63 mounted in the cover 22. The lower end of this operating lever 61 is bent horizontally as at 65 and partly encircles the combination drain and overflow cup 66 which, as illustrated in Figure 2, is provided with an overflow opening 67 which prevents the water 45 in the tub from becoming higher than desired so that the efficiency of the machine is not affected. This overflow cup is preferably of cylindrical formation and its bottom end is open and arranged to fit over the drain opening 68 in the bottom of the tub or tank, it being evident that operation of the lever 61 will cause a movement of the cup from over the opening 68 to let the water 45 discharge from the tub through the drain opening. The lower edges of the cup 66 may carry the sealing gasket 69 to prevent leakage of the water during a washing operation.

90 The end thrust of the motor shaft 33 is taken up by the ball 70 upon which the end of the shaft is mounted, the ball being held in position through the medium of the plug 13 which is threaded as at 71 interiorly of the sleeve 72. Suitable means are provided for the oiling of the motor, and the motor housing 16 is ventilated through the medium of a suitable conduit 73 which leads therefrom to a suitable plug opening 74 in the cover 22, it being understood, of course, that the electric wires from the motor 100 extend up through the conduit 73 and terminate in the plug 74 to which is connected any source of electric power terminating in a plug. The conduit 73 is made of waterproof material.

105 The main frame 9 is also provided with the corner pieces 75 defining pockets for cups, silver and other eating utensils which cannot be supported in the dish rack, this frame 75 being made of heavy wire and being secured to the main frame 9 and closed with a suitable mesh 110 76 to prevent the utensils from falling out or getting in the way of the impeller.

115 It is evident that the impeller operating under high speed, will take the water in at its lowermost end which is submerged and will project it in streams upwardly at high pressure and in fast moving jets so that the dishes are thoroughly cleansed by the impingement of the water thereon and are quickly and effectively cleansed.

120 It is quite evident that the motor may be oiled in any manner desired and the dish racks 27 and 19 may be vulcanized with a rubber covering, if so desired. It is to be noted that the motor is secured to the housing by suitable screws 135 16A which engage the motor casing and hold the motor in position. Also, the dish holding frame and main frame may be made in separate units if desired. A further function of the sleeve 145 72 is that it provides a bearing for the motor shaft 150

- and the impeller, and ball 70 constitutes a thrust bearing for the shaft of the motor, the ball resting freely on the plug 13 and centering itself under the motor shaft at which point suitable lubrication is provided. 5
- It is evident, therefore, that I have provided a washing machine consisting of main and auxiliary frames in the former of which the motor housing and impeller are supported as well as the cover and its associated parts which constitute a closure for a tub or tank in which the washing machine is positioned, the machine itself being adaptable for use in an ordinary wash tub thus eliminating expense to the purchaser in buying a casing especially fitted for the washing machine. 10
- My invention further provides for a washing machine which in taking its place in a wash tub does not occupy valuable space and can be quickly and easily removed when the tub is to be used for the washing of clothes or other purposes. 15
- My invention is not to be restricted to the precise details of construction shown since various changes and modifications may be made therein without departing from the scope of the invention or sacrificing the advantages derived from its use. 20
- What I claim is:—
- 30 1. The combination with a receptacle provided with a drain of a dish washing machine removably positioned in the receptacle, comprising an open wire frame, dish supporting members on said frame, a motor housing in the frame, a motor operated water projector, a cover supported by the frame, and a drain closure supported from said cover. 35

- 75
2. The combination with a receptacle provided with a drain of a dish washing machine removably positioned in the receptacle, comprising an open wire frame, rings on the frame, radially disposed dish holding members on said rings, said members cooperating to support a dish at the edge and inwardly from said edge, a cover on the frame, and a drain closure supported by and operable from said cover. 80
3. The combination with a receptacle having a drain of a dish washing machine removably positioned in the receptacle, comprising a main frame arranged to rest on the bottom of the receptacle, dish holders on the frame radially disposed about the vertical axis of the machine, a cover on the frame providing a closure for the receptacle, a lid hinged to said cover, a drain closure, and means for supporting and operating said closure from said cover. 85
4. The combination with a receptacle having a drain of a dish washing machine removably positioned in the receptacle, comprising a main frame, a top for the machine constituting a cover for the receptacle, a hollow drain closure, an opening in the upper part of said closure constituting a water overflow and a lever supported by the cover for operating the drain closure. 90
5. The combination with a receptacle having a drain, of a dish washing machine comprising an open frame, a water impeller, means for operating the impeller, dish supports on the frame, a cover for the receptacle supported on the frame, a lid hinged to the cover, a drain stopper, and means carried by the cover for supporting and manipulating said stopper. 95
